UNITED STATES PATENT OFFICE.

JOHN P. PETRARCA, OF ARCTIC, RHODE ISLAND.

PATTERN FOR SHOEMAKING.

1,425,278.

Specification of Letters Patent. Patented Aug. 8, 1922.

Application filed December 9, 1920. Serial No. 429,329.

To all whom it may concern:

Be it known that I, JOHN P. PETRARCA, a subject of the King of Italy, and a resident of Arctic, county of Kent, and State of Rhode Island, have invented certain new and useful Improvements in Patterns for Shoemaking, of which the following is a specification.

This invention relates to an improved pattern for cutting out the parts that go to make up a boot or shoe, and is designed to provide a set of frames which are in themselves adjustable so as to vary the sizes, both longitudinally and laterally, and which provide for a maximum adjustment in these directions, due to a lamination or the provision of the necessary number of strips to permit such variations in order that a shoemaker may fit any customer by means of the single pattern.

The invention is further designed to provide patterns for various parts of the shoe; for instance, a pattern for the upper, one for the vamp and one for the counter, these frames for the several parts being adapted to be secured together, if necessary, so that the frame for the counter can be secured to the frame for the vamp if the vamp and the counter of the shoe are to be made in one piece, or can be attached to the frame of the upper if the upper and the counter are to be made in one piece, or these parts can be used separately if the counter, the upper and the vamp are to be made up of separate pieces.

Another object of the invention is the provision of a frame around which a knife is to be used for cutting the upper of the shoe away and is provided with a bottom part and a top part, the bottom part being adapted to have its top edge define the upper of a shoe, the top part being added on to the bottom part, when necessary, to define the outline of a blank to make the upper or top of a boot, all these parts being adjustable.

The device is further adapted to provide a pattern or frame for a vamp which can be secured to the frame defining the shape of the counter, and is also adapted to receive an extension which defines a tongue, the extension being adapted to provide different outlines of tongue and being extensible in order to vary the dimensions of the tongue when necessary.

The invention is illustrated in the accom-

panying drawings, in which Figure 1 is a face view of a frame for use in cutting out the upper of footwear, and Figure 2 is a rear view of the frame shown in Figure 1, these figures also including, at their bottom portions, a removable frame for defining the counter of a shoe. Figure 3 is a top view of a frame used in cutting out the vamp. Figure 4 is a modified form of frame for defining the shape of the counter. Figure 5 is a view of a frame adapted to be attached to the lower front part of the frame for the upper shown in Figure 1. Figure 6 is a perspective view of a modified form of extension to be used on the frame shown in Figure 3 to define a short tongue. Figures 7, 8 and 9 illustrate different forms of shoes that can be made by the use of this device.

In Figure 1 I show a frame for use in cutting out the uppers, which frame has the bottom part 10 and the upper part 11, these parts having hinged corner joints or sections, the top part having its upper corners, as at 12 and 13, hinged together, and having strips, such as 14, on the top side, one of which is slotted, as at 15, and has a set-screw 16 by means of which it can be fastened in position. The side edges are provided with strips, such as 17 and 18, which are slotted and held in place by set-screws 19 and 20. The strips are held in substantial alignment by suitable means, such as the lips 21, which are folded over from one strip onto the edge of another, this being carried on throughout the structure so that the top bars 14, for instance, form an edge against which the cutting implement bears when the pattern or blank is being cut, a supplemental bar 22, which is similarly extensible, being adapted also to be used as a cutting edge, if necessary.

The strips 17 and 18 slide on the strips 23 underneath them, which, in turn, are slotted to provide for their adjustment, these, in turn, resting on the transversely movable plates 24 which are held, by set-screws 25 and screws that pass through the slots 26, on two opposed back plates 27, these back plates supporting the entire top part of the frame for the upper so that it can be supported by means of the screws 28 on the bottom part 10 of the frame for the upper, this being particularly evident from Figure 2. The pins 29 are pivotal pins, that is, they hinge the parts 27 and 22 together.

For the purpose of readjustment I prefer

to provide scales, such as the scales 30 and 31, on various parts of the mechanism, where desired, and I preferably construct the strips with pointers 32 to indicate on the scale the required measurement. The bottom part 10 has a pair of back plates 33 and 34 which provide, at their top edge 35, a cutting edge for the top of a shoe upper, these plates being slotted, as at 36, and having set-screws 37 to secure them together, the instep portion being hinged at 38 and having the strips 39 and 40 and the corner piece 41 which is hinged, as at 42, to the lower front strip 43, which, in turn, is slidably connected with the bottom strip 44 which has a companion strip 45, the bottom edges of which, as at 46, define the bottom of the upper, the strip 45 being hinged, as at 47, to the rear strip 48, all these strips being suitably slotted and provided with set-screws so that they can be held in adjusted position.

It will thus be seen that the one frame provides means for making a high upper, as at 49 in Figure 9, or a short upper, as at 50 in Figures 7 and 8.

Detachably secured to the bottom of the frame for the upper is a frame for the counter which comprises back plates 51 and 52 which are held in position by the bolts 53, 47 and 54, the front edge 55 of the back plate 51 being curved to define the front edge of the counter, and the back edge 56 of the back plate 52 defining the rear edge of the counter, these being adjustable and hinged, as at 57 and 58, to the bottom strips 59 which are also adjustable and have their bottom edges 60 to define the bottom edge of the counter, the frame for the vamp, as shown in Figure 3, having a main plate 61 with the adjustable supporting strips 62 at the front, to which is attached, by the hinged bolt 63, the central pair of a series of marginal strips 64 which are adjustably connected together, the rearmost of which, as at 65, are connected to supporting ribs 66 which are transversely adjustable, their inner ends being held longitudinally adjustable by the inside strips 67, which strips 50 have their inner edges to define the inner edge of the vamp, these parts being also movable transversely by means of the slotted supplemental plates 68, these supplemental plates having pins 69 on which are 55 adapted to be mounted small frames for defining the outlines of short tongues such as used in blucher shoes, one form being shown in place as at 70 in Figure 3, having its end strip 71 provided with holes which can be placed over the posts 69, or, in case the strips 70 are extended, the innermost of the holes in the end strips 71 of the tongue frame are placed over the outside post 69 and the inner end over the post 72.

65 A modified form of frame for a vamp is

shown in Figure 6 with its end strip 73 provided with holes 74 to go over the posts 69 and 72, as desired, the pointed strips 75 being thus adapted to form a round instead of a substantially square tongue, as provided by the strips 70 in Figure 3.

It will be evident that when the vamp is used alone it provides a frame that is utilized in a shoe as shown at 76 in Figure 7. The frame for the counter, shown in the lower part of Figure 1, can be shifted to occupy the position shown in dotted outline at 77 in Figure 3 so as to provide for cutting out on a single blank the vamp and the counter, as at 78 in Figure 8. The parts 80 are made interchangeable for this purpose, the holes 79 being provided for receiving the screw 53 which, with its set-screw, is shifted with the counter frame, the forward pivotal or hinged pin of the lower pins 80 85 of the counter frame being adapted to be placed through the slot 81 in the rearmost of the marginal strips 64 of the vamp pattern or frame.

In Figure 5 I show a frame to provide 90 for an extension on the counter shown in the lower part of Figure 1, which provides the outline of a low shoe or tie, this frame having its bottom strips 82 and 83 adapted to be secured to the back plates 51 and 52, 95 the bottom strip 83 having three holes, shown at 84, which are adapted to fit over the studs shown at 85 and at 53 in Figure 1, the rear corner hinge 86 being adapted to replace the pin 47 shown in Figure 1, the front curved strip 87 and the top strips 88, which are adjustably connected with their corners provided with the pivotal pins 89, defining the upper edge against which the cutting of the shoe is made, so that the 100 form shown in Figure 5 can be replaced by the counter frame shown in the lower part of Figures 1 and 2 and thus form the outline of the counter of a tie, and these two assembled, if desired, can be attached to the 110 vamp so as to provide for a one-piece pattern for the vamp and the counter and extending up at the front part in the style of the usual oxford or similar tie.

In Figure 4 I show a modified form of 115 frame to be used for outlining the counter adapted to be attached to the end of the vamp, the three studs 90 being adapted to fit in the holes 79 in Figure 3 and set-screws being used to clamp the parts in position, the bottom strips 91 and the back strip 92 and the front strips 93 being all connected together, as shown in the drawings, so that they are slidably arranged relative to each other, but, by means of set-screws, are held 120 in their adjusted positions.

It will be evident that I have thus devised a pattern for shoes, the several parts of which are usable independently and can be collected together in various combina- 130

tions to form combined patterns which make it possible to make boots, shoes, short vamps, long vamps and vamps in one piece with the counter, counters in one piece with 5 the uppers, and all from the same frames, the only necessity being for properly assembling them and then giving them the proper adjustment to indicate the size.

I claim:

10 1. A pattern for shoes comprising a frame for outlining an upper, a frame for outlining a vamp, a frame for outlining a counter, and means for securing the frame for the counter either to the frame for the 15 upper or that for the vamp.

2. A pattern for shoes comprising a frame for outlining an upper, a frame for outlining a vamp, a frame for outlining a counter, and means for selectively securing the frames to one another to provide patterns for shoes of various styles. 20

3. A pattern for shoes comprising a frame for a vamp, and detachable frames adapted to be interchangeably secured to the vamp frame for defining different 25 forms of tongues for the vamp.

In testimony that I claim the foregoing, I have hereto set my hand, this 4th day of December, 1920.

JOHN P. PETRARCA.
